UNITED STATES PATENT OFFICE

112,430

DESIGN FOR A SIGNBOARD

Alexander L. Bauers, La Grange, Ill., assignor to General Outdoor Advertising Co., Chicago, Ill.,
a corporation of New Jersey

Application September 12, 1938, Serial No. 79,844

Term of patent 7 years

To all whom it may concern:

Be it known that I, Alexander L. Bauers, a citizen of the United States, residing at 405 South Blackstone, La Grange, in the county of Cook and State of Illinois, have invented a new, original, and ornamental Design for a Signboard, of which the following is a specification, reference being had to the accompanying drawing, forming part thereof.

Fig. 1 is a front elevational view of a signboard showing my design;

Fig. 2 is a side elevational view thereof.

I claim:

The ornamental design for a signboard, substantially as shown.

ALEXANDER L. BAUERS.
